UNITED STATES PATENT OFFICE.

REINOLD V. SMITH, OF EUREKA, UTAH.

METHOD AND APPARATUS FOR SEPARATING ORE.

1,407,229.

Specification of Letters Patent. Patented Feb. 21, 1922.

Application filed December 10, 1917. Serial No. 206,470.

To all whom it may concern:
Be it known that I, REINOLD V. SMITH, a citizen of the United States, and residing at Eureka, county of Juab, State of Utah, 5 have invented certain new and useful Improvements in Methods and Apparatus for Separating Ore, of which the following is a specification.

The present invention relates to improvements in method of and apparatus for separating or sizing ore and is particularly adapted for separating relatively finely divided ores.

By the constructions heretofore employed, 15 it has been practically impossible to separate or size ores which will pass through screens of from 120 to 150 mesh and finer. By the method and apparatus hereinafter described, it is possible to separate a body 20 of ore into three grades or sizes, namely, an over-size which will not pass through the fine mesh screen but requires regrinding, second, a fine granular product that passes through the screen, and third, a slime 25 product.

In the accompanying drawings:

Figure 1 is a plan of an apparatus adapted to carry out the present invention;

Figure 2 is a longitudinal vertical section 30 of such apparatus;

Figure 3 is an end view;

Figures 4 and 5 are diagrammatic views illustrating the movement imparted to the separating screen;

Figure 6 is a detail sectional view of the screen and its supporting frame.

Referring to the drawings, 1 designates a water tank or receptacle, the bottom portion of which is divided by suitable walls into 40 two chambers or compartments 2, 3, and which is further provided with a water supply or inlet pipe 4 and an overflow or waste pipe 5.

A screen 6 is supported in a longitudinally inclined position within the tank below the water level therein in such a manner that when it is vibrated laterally, the side portions thereof will be more violently vibrated than the intermediate, middle portion, whereby the finer particles of a body of ore deposited on the screen will be caused to pass through the screen into the compartment 3 at the bottom of the receptacle of the tank 1, while the larger oversize particles 55 will be collected in the middle portion

of the screen and caused to travel downwardly over the lower end into the compartment 2.

As shown the screen is supported by links 7, the upper ends of which are pivotally connected with standards 8 rising from the walls of the tank 1. The upper ends of the links 7 are spaced apart a greater extent than the width of the screen supporting frame to which the lower ends are connected so that said links occupy an inclined position as represented in Figures 3 to 5. Means are provided for vibrating the screen laterally which, as shown, comprise an arm 9 rising from the screen supporting frame and a link 10 connecting said arm with a crank 11 on a shaft 12 mounted in suitable bearings on the tank and provided with a driving pulley or belt wheel 13. The extent of the vibration of the screen frame may be varied by connecting the link 10 with the arm 9 at different points in its length, said arm being shown as provided with a plurality of vertically spaced apertures with any one of which the link 10 may be engaged.

Referring to the diagrammatic views 4 and 5, it will be seen that the vibratory movement of the screen is in effect about three different arcs, the side portions being more violently vibrated or moved through a greater distance than the intermediate middle portion. As before noted, the entire screen is submerged in the water in the tank 1 and the alternate lifting and suction of the water together with the relative violence of the motions at the middle and edge portions of the screen acts to throw the coarser particles of ore to the top in the middle section of the screen and draw the smaller particles through the side portions thereof. These motions keep the body of oversize material travelling downward and turning over on the screen in the middle section thereof, leaving the side portions free to permit the escape of the small particles into the compartment 3. The body of ore assumes on the screen the position indicated in Figure 1. The settlement of slime is prevented by the gradual movement of the body of ore together with the agitation of the water due to the movement of the screen and such slime is carried off through the outlet pipe 5 by the current of water which, it will be noticed, is in the direction corresponding to 110

the upward inclination of the screen. Each of the compartments 2, 3, is provided with a suitable outlet through which the contents thereof may be withdrawn as desired and 5 the ore to be treated is supplied to the screen 6 by any suitable means, not shown.

The screen 6 is secured in the vibrating frame by means which can be readily disengaged, for example, suitable set screws, so 10 that the screen may be readily removed and replaced by another whenever desired.

While the drawings illustrate one means which may be employed for vibrating the screen as described, it will be evident that 15 the invention is not limited to the use of this particular means, as other devices may be provided for imparting similar motion to the screen.

Having thus described the invention, what 20 is claimed is:

1. The herein described method of separating ore comprising supplying ore to an elongated screen submerged in water, and positioned to cause the ore to pass toward 25 one end thereof, and vibrating the screen in and with relation to said water laterally of the direction in which the ore travels over the screen, the vibrating movement being sufficiently more violent at the sides of the 30 screen than at the intermediate middle portion as to cause the coarser particles of ore to collect on top at the middle portion and the finer particles to pass through along the side portions.

35 2. The herein described method of separating ore comprising supplying ore to a screen submerged in water, and positioned to cause the ore to pass toward one end thereof, vibrating the screen laterally of 40 the direction in which the ore travels over the screen, the vibrating movement being more violent at the sides of the screen than at the intermediate middle portion, and causing a current of water to flow over the 45 screen in a direction opposite to the path of movement of the ore thereon.

3. The herein described method of separating ore comprising supplying ore to a screen so submerged in water as to permit 50 water to pass over it freely from the sides and so positioned as to cause the ore to pass toward one end thereof and vibrating the screen laterally of the direction in which the ore travels over the screen, the vibration 55 of the sides of the screen including alternate up and down movement whereby there is sufficiently more violent agitation along the sides than in the center to cause heavy material to collect in the central portion.

60 4. An ore separating apparatus comprising a water tank having means for supplying water thereto and an elevated outlet, a screen supported within the tank below the water level, and inclined to cause ore to 65 move thereover in a direction opposite to

the flow of water through the tank, means for vibrating the screen laterally of the direction in which the ore and water travel thereon, the vibrating movement being stronger adjacent the sides of the screen 70 than at the intermediate middle portion, and two receptacles adapted, respectively, to receive the material passing through the screen and that delivered from the discharge end thereof. 75

5. An ore separating apparatus comprising a water tank, means for creating a flow of water through the tank, a screen supported in a longitudinally inclined position downwardly from its receiving end to its 80 discharge end beneath the level of water in the tank, the inclination of the screen being upward in the direction of flow of water, and means for vibrating the screen laterally. 85

6. An ore separating apparatus comprising a water tank, a screen supported in a longitudinally inclined position in the tank below the level of water therein and adapted to have the water in said tank pass over it freely from its edges, and means for imparting lateral vibration to the screen adapted to vibrate the side portions thereof more violently than the intermediate portion. 90

7. An ore separating apparatus comprising a water tank, having two compartments or receptacles in its bottom, a screen supported in a longitudinally inclined position over said receptacles and beneath the level of water in the tank, and means for vibrating the screen laterally. 95

8. An ore separating apparatus comprising a water tank, an elongated screen suspended in said tank below the water level inclined longitudinally and adapted to receive ore at its upper end, and sufficiently removed from the walls of the tank to permit lateral and vertical movement, means for vibrating the screen laterally and at the same time vibrating one side upward 105 and the other downward unequal amounts. 110

9. An ore separating apparatus comprising a water tank, an elongated screen suspended in said tank below the water level inclined longitudinally and adapted to receive ore at its upper end and sufficiently removed from the walls of the tanks to permit lateral and vertical movement, means for vibrating the screen laterally and at the same time vibrating one side upward 115 and the other downward unequal amounts, and means for keeping separate material passing through the screen and material passing over the lower end of the screen. 120

10. An ore separating apparatus comprising a water tank, an elongated screen suspended in said tank below the water level inclined longitudinally and adapted to receive ore at its upper end and sufficiently removed from the walls of the tank to per- 125 130

mit lateral and vertical movement, means for vibrating the screen laterally and at the same time vibrating one side upward and the other downward unequal amounts, and 5 means for keeping separate material passing through the screen and material passing over the lower end of the screen, a water in-

let for said tank below the screen at one end, and a water outlet above the screen at the other end. 10

In testimony whereof I affix my signature.

REINOLD V. SMITH.
